UNITED STATES PATENT OFFICE.

HARRY S. MOIR, OF CHICO, CALIFORNIA, ASSIGNOR, BY DIRECT AND MESNE ASSIGNMENTS, TO THE MOIR CALCULATOR CORPORATION, OF SAN FRANCISCO, CALIFORNIA, A CORPORATION OF CALIFORNIA.

CALCULATOR.

Application filed May 16, 1923. Serial No. 639,235.

To all whom it may concern:

Be it known that I, HARRY S. MOIR, a citizen of the United States, residing at Chico, county of Butte, State of California, have 5 invented certain new and useful Improvements in Calculators; and I do declare the following to be a full, clear, and exact description of the same, reference being had to the accompanying drawings, and to the characters of reference marked thereon, which 10 form a part of this application.

This invention relates to a device to be used in connection with special forms of interest and other tables, to readily find, indicate and display the desired result from the tables, without mental or other figuring, and in a quicker and easier manner than could be done if the tables were used alone.

The device is particularly designed and 20 intended for use in connection with the tables such as are shown in my Patent No. 1,383,227, dated June 28th, 1921, on a savings bank interest indicator, and the device or 25 mechanical apparatus in itself is an improvement over the device shown in said patent, and also over that shown in my co-pending application on an interest indicator, Serial No. 505,296, filed October 4th, 1921.

30 In both of these former devices only one tabulated page or sheet of figures could be placed therein, which therefore limited the use of the apparatus considerably. Since then, however, I have compiled a number of 35 sheets of tabulated figures of different natures, which I may add to in the future, and which include savings-bank interest tables; simple and compound interest tables for general use; contract-payment computation tables; tax rate and payment tables; multiplication and similar tables; dollar conversion 40 tables for use when dealing with foreign exchange; and any other similar tables which may be prepared, and the tabular figures 45 thereon arranged in such a manner that my calculating device may be used in finding any desired results from such tables.

As above stated, only one at a time of any 50 such tables could be placed in my device as originally designed, and to remove and replace such table with another necessitated practically taking the device apart, which at

best was a very inconvenient procedure, and entailed a great loss of time.

The principal object of the present invention therefore is to construct the calculating device used in obtaining the results from the tables in such a manner that all the tables may be placed therein at one time, and any desired table of the lot used without removing 55 the remainder from the calculator, and without having to detach any part of the latter.

At the same time, the tables may be removed as a unit very quickly and easily, when it is desired to remove certain ones 60 removed therefrom or add other tables thereto, or change the relative locations of the tables, or for any other purpose.

I have also provided means for enabling 65 the device to rest flat on a desk or table, or to set at an angle thereto, with a simple means for insuring that the device will remain in the latter position until it is intentionally lowered.

A further object of the invention is to 70 produce a simple and inexpensive device and yet one which will be exceedingly effective for the purposes for which it is designed.

These objects I accomplish by means of 75 such structure and relative arrangement of 80 parts as will fully appear by a perusal of the following specifications and claims.

In the drawings similar characters of reference indicate corresponding parts in the 85 several views.

Fig. 1 is a top plan view of the calculator with the tables in position therein.

Fig. 2 is a perspective view of the device alone, with the tables removed.

Fig. 3 is a perspective view of the tables 90 with their holder, detached from the calculator.

Fig. 4 is a longitudinal section of the device, with the table-unit removed and with the supporting legs partly folded.

Fig. 5 is a similar view, with the legs fully 95 folded and with the table-unit mounted therein.

Referring now more particularly to the 100 characters of reference on the drawings, the device comprises a holder or container consisting of a flat, rigid and rectangular board or base 1, on which side rails 2 and top and bottom rails 3 and 4 are fixed, said rails pro-

- jecting both above and below the base, but mainly above.
- Pivoted on and under the base at the upper corners thereof are legs 5 having longitudinal slots 6 cut therein, said legs being of a length sufficient to support the base at a suitable angle when the legs are vertically disposed, and being adapted to fold up to lie against the base and to then extend lengthwise thereof.
- Pivoted in locations similar to the legs but at the lower end of the base are brace arms 7, having pins 8 slidable in the slots 6, the pins of said arms being at the upper ends of the slots when the legs are folded and the arms being then likewise folded against the base; and the pins being at the lower ends of the slots when the legs are outstretched.
- To hold the legs and arms in the latter position, I provide a latch bar 9 pivoted for movement in a plane at right angles to the legs on the cross member 10 which connects the outer ends of the legs, the outer end of said bar 9 having an offset portion 11 adapted to frictionally pass over and engage a cross rod 12 extending between the arms 7 when said arms and legs are outstretched.
- Rubber feet 13 are provided on the bottoms of the sides 2 to support the device when resting flat on a desk, the lower feet also functioning when the legs are in use.
- Mounted on the base 1 adjacent the lower rail 4 and extending between the rails 2 is a step or block 14 of a lesser height than said rails. Extending lengthwise of the side rails just above the block 14 are guide grooves 15 for the crossheads 16 of a result-finding device comprising a transverse slide-frame 17, movable from top to bottom of the device, being of course limited in such movement by the top and bottom rails 3 and 4.
- Openings 18 are cut through the slide at the ends thereof, intermediate which is a continuous groove 19, terminating in a narrow slot 20 cutting through the underside of the slide.
- A plurality of independent shutters 21 is slidably mounted in the groove 19, in any suitable manner, the total length of the combined shutters being less than that of the groove, so that a space of certain and predetermined width may be had between any two shutters by suitably moving the same, to expose the slot 20 thereunder, as shown in Fig. 1.
- Adapted to be placed in the container and to rest on the base 1 and to extend with a fairly close fit between the side and top rails and the block 14 is a rigid board 22, at the upper end of which is a lug 23 adapted to slide into and fit a correspondingly shaped transverse groove 24 cut in the top rail 3 just above the base. The lower end of the board then lies adjacent the inner edge of the block 14, the main function of which is to act as a stop to prevent longitudinal downward movement of the board on the base.
- Intermediate the side edges of the board the lower end of the latter is cut away for a certain distance as at 25, for a purpose as will appear.
- Mounted on the upper face of the board 22 and detachably secured at the upper end thereof as by screw binders 26 common to loose-leaf devices are sheets 27 having different tables of figures as at 28 thereon, arranged in columns so as to coincide with the openings 18 in the slide 17 and with the differently located spaces obtainable between the shutters carried thereby. The sheets are hinged transversely below the binding means 26, so that they may be raised up from the lower end without disturbing said means, as are the leaves of a book. The sheets and board 22 thus form a pad complete in itself.
- The lower ends of the sheets terminate about in the plane of the upper edge of the cutaway portion 25 of the board 22, and have tabs 29 extending therebelow in staggered relation, said tabs being suitably marked so as to serve as indices to the character of the sheets without first raising them up to determine this.
- The board 22 being relatively thick compared to the sheets, the cutaway opening 25 leaves a space over which the tabs hang, thus making it easier for the operator to insert a finger under and grasp any tag the sheet connected to which he may desire to raise.
- The width of the slide relative to that of the stop block 14 is such that when the former is moved to its lowermost position in the container, the upper edge of the slide will not extend forwardly of the corresponding edge of the stop, so that no interference with the ready raising of any sheet, or the removal of the sheet-pad as a whole, is had.
- The slide must of course be moved to the above named position before any sheet can be raised or the pad removed, but this is of course but the matter of a second to accomplish.
- It is evident of course that to use any sheet those above must be raised and folded back out of the way, and that as many sheets may be used in the pad as can be accommodated under the slide.
- The method of computing or finding interest and the like with the aid of this device forms no part of this invention, this feature having been taken up in the aforementioned patent and copending application; but I will give a single illustration

of the method of finding the interest at a certain per cent rate on a certain number of dollars and for a definite period of time.

A plain interest table is that shown in Fig. 1, and I will assume that it is desired to find the interest on \$20,000.00 for 61 days at 7%. The table has certain vertical columns A of days which are in alinement with the opposed slide-openings 18, into which 10 pointers 18^a project.

Between the columns A are other columns of figures B which represent the different interest amounts, at 7 and 8% rates, on the sums, or decimal multiples or parts there- 15 of, which are at the heads of the columns B.

The slide 17 is then moved up or down as may be necessary, until the pointers 18^a aline with "61" in the day columns.

The necessary shutters 21 are then moved 20 to uncover that portion of the slot 20 which is in vertical alinement with the columns headed "\$20,000.00." Since said slot is also in transverse alinement with the pointers 18^a, the line of figures of the B columns 25 visible through said slot will give the result desired; two adjacent B columns, both for the same amount of principal, but one figured at 7% and the other at 8%, being disclosed at one time if the remainder of 30 the shutters are abutted against each other, so that the operator can obtain both the 7% and 8% interest amounts at one reading if desired. These interest figures are not pointed off with decimal points, this being 35 done by the operator, using his judgment in connection with the knowledge of mathematics which any bank clerk or official must have.

The upper face of the slide has various 40 indicia or guide designations thereon as at C, some of which are of use with certain of the tables, while others are used only with other tables, in this manner making the single slide usable with all the tables, 45 and making it easier for the operator in effecting his calculations and getting the desired results.

From the foregoing description it will be

readily seen that I have produced such a device as substantially fulfills the objects of 50 the invention as set forth herein.

While this specification sets forth in detail the present and preferred construction of the device, still in practice such deviations from such detail may be resorted to 55 as do not form a departure from the spirit of the invention, as defined by the appended claims.

Having thus described my invention what I claim as new and useful and desire to se- 60 cure by Letters Patent is:

1. In a calculating device, a container for a computation sheet having a compartment to receive and maintain the sheet in a horizontally immovable but vertically removable position, a finding element disposed in a fixed horizontal plane and slidable over the sheet, and guide means for the element mounted on the container, such guide means being disposed beyond the edges of the sheet 70 and having a length relative to that of the sheet to enable the element to be moved clear of said sheet, whereby the sheet may be moved in a vertical direction without interference with the guide means or finding element. 75

2. In a calculating device for use with a pad of computation sheets hinged together at one end, a container having sides to maintain the pad in a fixed but removable horizontal position without interfering with the upward swinging movement of the sheets about their hinge, a finding element movable over the surface of the pad, and guide means for the element mounted on the 80 container to the sides of the pad to maintain the element in a definite horizontal plane and extending beyond the end of the pad opposite to the hinge thereof a sufficient 85 distance to enable the element to be moved entirely clear of the pad without raising said element from the container. 90

In testimony whereof I affix my signature.

HARRY S. MOIR.
